YARN GUIDE FOR KNITTING MACHINES

Gustav Gastrich, Wyomissing, Pa., assignor to
 Textile Machine Works, Wyomissing, Pa., a
 corporation of Pennsylvania

Application March 14, 1935, Serial No. 11,050

18 Claims. (Cl. 66—126)

This invention relates to straight or full-fashioned hosiery knitting machines, and more particularly to the thread carriers or guides, carried by the reciprocating thread feed rods of such machines.

In present day knitting machines of the above-mentioned type, many difficulties arise due to improper construction of the yarn guides, which are carried by the thread carrier bars.

10 The holder, and the carrier arm of such devices, are of such construction and dimensions, that a relatively long unguided length of yarn extends from the end of the holder to the delivery tube. This construction permits the yarn to whip back and forth across the lower end of the carrier, often causing breakage of the yarn, particularly at the high speeds at which the carrier bars are operated in modern machines.

Another disadvantage of existing structures of 20 this type is apparent in the use of three carrier alternating devices, wherein it is necessary to lead one of the threads to one of the yarn carriers from a point above and in front of the yarn carrier assembly. In doing this, it is impossible to 25 make use of the existing guide apertures in the holder, and the thread is unguided until it enters the groove passing down over the depending portion of the carrier arm.

Another difficulty becomes apparent, in the 30 use of high twist yarn, in that the present day construction of yarn carriers permits the thread to kink and buckle, upon the release of the tensioning devices.

One object of this invention is to produce a 35 novel yarn guide device of the type referred to which will eliminate the above and other difficulties incident to the feeding of the yarn across the sinkers and dividers.

Another object of this invention is to obviate 40 the above difficulties by constructing a novel yarn guide assembly with a view to eliminate the injurious effect of the unguided length of the thread carrier, and, at the same time, to maintain the usual length thereof.

45 Another object of this invention is to provide means for positively guiding the yarn at a point intermediate the delivery tube and the lower end of the carrier arm holder.

Another object of the invention is to provide a 50 guiding means along the unguided length of the thread carrier for the purpose of facilitating the use of "high-twist" thread.

Another object of this invention is to provide 55 an auxiliary guide member which can be adjustably attached to thread carrier assemblies on

existing installations with ease and precision, and without in any way disturbing the organization of parts.

With these and other objects in view, which will become apparent from the following detailed 5 description of one embodiment of the invention shown in the accompanying drawing, the invention resides in the novel elements, features of construction and combination of parts in cooperative relationship as more particularly pointed 10 out in the claims.

In the drawing:

Figure 1 shows a perspective view of various parts of a "Reading" full fashioned knitting machine, embodying the mechanism and elements of 15 my invention;

Fig. 2 illustrates in section, a thread carrier mounted on a carrier rod, having a preferred form of the specific auxiliary guide affixed thereto; and

Fig. 3 illustrates a plan view of a preferred form 20 of the auxiliary thread guide per se.

For clearness, only those parts of the various mechanisms necessary for an understanding of the invention are illustrated, the other parts and 25 mechanisms and their manner of operation being well known in the art, as shown and described in the "Reading" Full Fashioned Knitting Machine Catalogue, copyright 1929, and published by the Textile Machine Works, Reading, Pennsylvania. 30

Referring to the drawing, and specifically to Fig. 1, a sinker-head assembly comprises elements 1 to 5, inclusive. The sinker-head bottom 1 has milled on the top surface thereof, a series 35 of equally spaced slots. Spaced from, and directly above the sinker-head bottom is the sinker-head top 2 having milled on its bottom surface a series of equally spaced slots. Upon assembly of these parts, the slots in both of the elements 1 and 2 are substantially perfectly aligned. Located within these slots are positioned alternately the sinkers 4 and the dividers 5. These last two elements are mounted for reciprocation by the slur-cock and catch bar. Mounted upon the 40 sinker-head top 2, is the verge plate 3 for limiting the forward movement of the sinkers.

The knitting needles 6 are spaced in accordance with the gauge of the fabric to be knitted, and to provide sufficient clearance for the passage 45 therebetween of either a sinker or a divider. Backward of, and above, the sinker-head assembly, are located the yarn carrier rods 9, which function to throw the yarn carriers so that the latter lay the thread along the noses of the 50 sinkers and dividers, and between the needles 55

and the sinker-head top. The yarn carrier rods derive their motion from the coulier cam by virtue of levers and friction box connections, as clearly indicated in the above-mentioned catalogue. Rigidly mounted on the yarn carrier rods, by means of cap screws 16, is a yarn carrier holder 8, as of sheet metal. This element has punched therefrom an integral ear 15 having an aperture therein for guiding the yarn. At the rearward portion of said yarn carrier holder, a portion 19 of the holder is bent upwardly, also having an aperture therein, aligned with the aperture in the ear 15. At the lower extremity of the holder 8, are two spaced elongated apertures or slots 18, the purpose of which will be hereinafter more fully explained.

Attached to the back of the yarn carrier holder 8, is the yarn carrier arm 7. This element comprises an elongated member bent at its forward lower end for the purpose of passing down over the sinker-head top and approaching the sinkers and dividers as nearly as possible, without interfering with their reciprocating motion. These carrier members, when used in a plural sense as for example in a three carrier alternating device, are formed at various angles to facilitate passing each other during operation.

At the upper extremity of the member 7, are two threaded apertures aligned with the slots 18 of the member 8, for receiving screws 14. Located at the end of the member 7, farthest from the point of attachment to the holder, is a tube 20 having a bore of determined diameter, depending upon the gauge of yarn or thread used. This tube 35 is secured, usually by soldering, to the thread carrier along its longitudinal center line. Directly above the tube, and leading from the bore thereof upwardly a substantial distance beyond the bend in the thread carrier 7, is a groove 21. This groove functions in aiding to guide the yarn or thread into the tube.

In the construction and manufacture of the carrier arm, incident to the grooving and bending of the end portion, and the soldering of the 45 delivery tube thereto, the surface is filed and polished to present as smooth a surface as possible. However, it often occurs that infinitesimal particles of roughness remain on this surface, so minute as to ordinarily avoid detection. Nevertheless, this surface is sufficiently rough to break a fine silk thread in the event that it jumps from the groove, and whips back and forth over this surface.

Mounted on the upper face of the yarn carrier holder 8, by means of screws 14, is an auxiliary yarn guide member 10, as shown in Figure 3. This member is somewhat of the shape of the carrier arm 7, except that it is only about half as long, and has its lower end portion bent oppositely to that of the end portion of the carrier arm 7. This auxiliary guide member is bent during assembly to fit the particular form of the carrier to which it is applied, so that its lower front portion contacts the thread carrier arm 7. The auxiliary member 10 is also provided with two spaced apertures which will properly align with the threaded apertures in the member 7, and the elongated apertures in the holder 8, to receive the screws 14. At the extreme front portion of the element 10, is the bent portion having an elongated aperture 11 therein. This aperture 11, is aligned with an aperture 18 in a raised ear portion 12 near the upper extremity of the member 10, and due to its elevated front portion, permits the yarn to freely pass to the groove 21, and

thence to the tube 20. The function of the elongated openings 18, is to facilitate proper alignment of the individual members making up the yarn carrier assembly.

It is to be noted that the apertures, namely those in the portion 19, the ear 15 and the portion 12, and the aperture 11, are all aligned with the groove 21, and hence with the tube 20. In this manner, a yarn carrier of improved form and exceptional use is provided, since by such construction, no great length of unguided yarn can be present along the carrier arm. This carrier assembly also provides a guide in the form of the aperture 11 for the yarn in three carrier alternating devices, where the thread for the top yarn carrier only does not pass down through the apertures in the guides 19, 15 and 12, but must pass down at a substantial angle to the carrier in a vertical plane, as shown by dot and dash lines in Figure 2, in order to avoid tangling with other threads.

This new and improved device also provides a means whereby "high twist" yarn will not buckle and kink along the thread carrier.

Of course, the improvements specifically shown and described, by which the above results are obtained, can be changed and modified in various ways without departing from the invention herein disclosed and hereinafter claimed.

I claim:

1. In a knitting device, the combination with a yarn carrier supporting member, of a yarn carrier arm mounted thereon, means guiding a thread along the longitudinal center line of said yarn carrier supporting member, and auxiliary guide means having an upturned end portion and a plurality of guide apertures located along the body portion thereof adapted to guide the yarn along the longitudinal center line of the yarn carrier arm.

2. A yarn carrier for straight knitting machines employing high twist yarn, the combination therewith of auxiliary yarn guide means adjustably mounted upon said yarn carrier comprising longitudinally spaced guiding means preventing kinking and buckling of the yarn upon the release of tension thereto.

3. In a yarn carrier for straight knitting machines, the combination therewith of adjustable means guiding the yarn only along the upper surface thereof, said means including an auxiliary yarn guide member having a series of aligned guide apertures spaced along the longitudinal centerline thereof, and cooperating with guide means spaced above said member and independent thereof whereby the yarn is supported at intervals throughout the entire length of said yarn carrier.

4. In a straight knitting machine including a row of needles, sinkers and dividers adapted to be passed through alternate needles; means for throwing a thread of yarn across the sinkers and dividers comprising a support containing yarn guide means, a thread carrier arm mounted on said support; of means adjustably mounted on said support and cooperating with the guide means in said support and positioned centrally of said thread carrier arm preventing lateral whipping of the thread.

5. A three piece yarn carrier comprising a support having aligned guiding apertures adapted to be mounted on a carrier rod, a second member attached to the support having a downwardly projecting end portion remote from the point of attachment to the support, and a third

member mounted in juxtaposition to said former members having an oppositely projecting end portion from that of the second member, said third member including a plurality of aligned apertures one of which is an elongated eye positioned in said oppositely projecting end portion, and means in said support facilitating the accurate alignment of all of said apertures.

6. A yarn carrier assembly comprising a yarn carrier support including an apertured up-turned end portion, an up-turned central portion having an aperture aligned with the first aperture, a yarn carrier arm mounted on said support, and yarn guiding means mounted on said members comprising an elongated member having an up-turned end portion with an elongated aperture therein, and means for adjustably locking said members together, whereby all the members can be locked with their respective apertures in alignment.

7. A knitting machine including in combination, a yarn carrier support provided with yarn guiding means mounted on a carrier rod, a relatively long yarn carrier arm, compared to the length of the support, mounted on said support, and a member adjustably mounted on said support and having means for guiding the yarn at two spaced points intermediate the ends of said yarn carrier arm.

8. In a knitting machine having in combination, a series of needles, sinkers and dividers adapted to be passed between alternate needles, a yarn carrier including a carrier arm support, the combination with said carrier, of auxiliary means adjustably mounted on the carrier support including yarn guiding means effective throughout the entire length of the carrier to prevent whipping of the yarn during operation of the carrier.

9. A yarn carrier assembly comprising a support provided with yarn guiding means, and having elongated openings, a carrier arm mounted on said support and provided with a downwardly depending portion, tube means affixed to the end of said depending portion, and a groove in the surface of the carrier arm extending from the tube means to a point substantially above the depending portion, and auxiliary guide means mounted on said support and rigidly attached thereto by screws in said openings passing through all the members, said auxiliary guide means extending down along the carrier to a point adjacent to the terminus of the groove.

10. In a knitting device, the combination of a yarn carrier including an upper base element for attachment to a carrier rod, a finger element extending forwardly and downwardly therefrom, each of said elements carrying a yarn guide, and means for adjustably securing the base and the finger in fixed relative position, of means mounted on the carrier by said adjusting means and providing an auxiliary yarn guide for cooperation with said first yarn guides and intermediate said guides.

11. In an article of the class described, an auxiliary yarn guide member, said member consisting of an elongated lower portion provided with guiding means at its lower end and arranged to extend along the upper surface of a yarn carrier arm with said guiding means positioned in close proximity to guiding means at the lower end of said arm, and a widened upper end portion provided with means arranged to receive fastening means.

12. A yarn carrier assembly comprising a yarn carrier support, a yarn carrier arm provided with guiding means at its lower end and mounted on said yarn carrier support, an auxiliary yarn guide removably mounted on said support and provided with yarn guiding means at its lower extremity, said auxiliary yarn guide arranged to guide a yarn to said means and extending from said support to a point in close proximity to said guiding means on said yarn carrier arm.

13. A yarn carrier assembly comprising a yarn carrier support, a yarn carrier arm mounted on said support, provided with a bent lower portion and supporting a yarn guide tube at its lower extremity, a groove in the upper surface of said arm extending from the end of said tube upwardly beyond said bent portion and in alignment with said tube, and an auxiliary yarn guide removably mounted on said support and provided with guiding means positioned adjacent the upper end of said groove.

14. In a full fashioned knitting machine, in combination, a yarn carrier arm extending forwardly and downwardly and having a main yarn guide at its lower end, an auxiliary guide member having a guide spaced above said main guide on the upper side thereof and having an elongated guide opening therein and arranged to direct a thread to said main guide when such thread reaches the auxiliary guide at any angle between the vertical and the angle of the arm, a support for said arm and member, and means for clamping said arm and member simultaneously to said support.

15. A knitting machine including in combination, a yarn carrier support provided with yarn guiding means mounted on a carrier rod, a relatively long yarn carrier arm, compared to the length of the support, mounted on said support, and means directly mounted on said support and adjustable thereon for guiding the yarn intermediate the ends of said yarn carrier arm.

16. In a knitting machine, in combination, a yarn carrier support provided with yarn guiding means and adapted to be mounted on a carrier bar, a relatively long yarn carrier arm, compared to the length of said support, mounted on said support and extending forwardly and downwardly and having a main yarn guide at its lower end, a member removably attached to said support and having auxiliary guides both at its upper and lower ends and arranged intermediate said guide means on the support and the guide at the lower end of said arm, the lower end of said member comprising a slot in a horizontal portion projecting from the upper side of said arm whereby such lower auxiliary guide is adapted to direct a thread to said main guide when such thread reaches the auxiliary guide at any angle between the vertical and the angle of the arm.

17. In a knitting machine, in combination, a yarn carrier support provided with yarn guide means and adapted to be mounted on a carrier bar, a relatively long yarn carrier arm, compared to the length of the support, mounted on said support, a member having auxiliary yarn guide means thereon directly mounted on said support, intermediate the guiding means on the support and the lower end of said arm, and fastening means acting simultaneously on said arm and member to clamp them to said support.

18. In a knitting machine, in combination, a yarn carrier support provided with yarn guiding means and adapted to be mounted on a carrier

bar, a relatively longer yarn carrier arm, compared to the length of the support, mounted on said support and extending forwardly and downwardly and having a main yarn guide at its lower end, a member having auxiliary guides one

5 at its upper and another at its lower end directly

mounted on said support, and fastening means for securing said arm and member to said support simultaneously and arranged also for simultaneous adjustment of the arm and member on said support.

GUSTAV GASTRICH.
